UNITED STATES PATENT OFFICE

118,642

DESIGN FOR A WASHING DEVICE

John Brendan McDonnell and Richard Baum
Raynolds, Tuckahoe, N. Y.

Application May 17, 1939, Serial No. 85,042

Term of patent 7 years

To all whom it may concern:

Be it known that we, John Brendan McDonnell and Richard Baum Raynolds, citizens of the United States of America, residing at Tuckahoe, New York, have invented a new, original, and ornamental Design for a Washing Device, of which the following is a specification, reference being had to the accompanying drawing, forming part thereof.

The single figure is a perspective view of a washing device showing our new design.

We claim:

The ornamental design for a washing device, as shown.

JOHN BRENDAN McDONNELL.
RICHARD BAUM RAYNOLDS.
